UNITED STATES PATENT OFFICE.

CHARLES W. EDDY, OF EAST PROVIDENCE, RHODE ISLAND.

METAL-PLATING MACHINE.

1,342,899.

Specification of Letters Patent.

Patented June 8, 1920.

Application filed April 29, 1919. Serial No. 293,555.

To all whom it may concern:

Be it known that I, CHARLES W. EDDY, a citizen of the United States, residing at East Providence, in the county of Providence and 5 State of Rhode Island, have invented a new and useful Improvement in Metal-Plating Machines, of which the following is a specification.

This invention relates to certain new and 10 useful improvements in a metal plating machine and more particularly to the washing and coating of small articles such as screws.

The principal object is to provide a machine for facilitating the several operations 15 by carrying on the various steps of washing, coating or plating and drying the articles entering the machine at one end in their unfinished state and discharging at the opposite end with a metal plate finish without the intermediary of manual handling or control.

The invention further resides in an improved electrode arrangement whereby one 20 of the two electrodes employed is disposed out of the plating solution whereby the same will not become coated with the solution.

Other objects are to improve the washers and driers for the articles, the invention consisting in the features of construction and 25 the arrangements and combinations of parts hereinafter described and claimed, reference being had to the accompanying drawings wherein—

30 Fig. 1 is a longitudinal section through the machine.

Fig. 2 is an end elevation thereof with a part of the feed hopper broken away and depicting the drive mechanism.

35 Fig. 3 is a vertical transverse section through the machine immediately beyond the drive mechanism.

Fig. 4 is a similar view through the pickling drum into which the articles are initially conducted.

40 Fig. 5 is a like view through the plating drum illustrating the electrodes and their mounting.

Fig. 6 is a detailed section through the 45 driving disks as mounted on one of the drive shafts.

Fig. 7 is a lengthwise section through an improved drying drum, and

50 Fig. 8 is a transverse section therethrough. 55 In proceeding in accordance with the present invention, a suitable supporting structure or frame is provided having spaced

rows of standards 1 formed with shaft bearings in which the shafts 2 are journaled, the same being driven through worm gears 60 3 by a transverse common shaft 4 deriving its power from a suitable source of power as transmitted by the belt and pulley connection 5. Fixed on the shafts 2 are alternate pairs of large and small friction disks 65 or wheels 6 and 7.

The pickling drum 8 is supported between and on the first pair of wheels 7 on each shaft, being rotated thereby as the shafts are driven; said drum having a pair of peripheral rims 9 resting on said wheels. Intermediate the rims the drum is radially enlarged to provide a pickling chamber which has peripheral perforations 10 whereby the pickling fluid may readily gain entrance to 75 the interior. A supply trough 11 is supported above the base of the frame between the spaced drum rims 9 so that the perforated periphery will have its lower arc disposed in or passing through the pickling 80 liquid contained therein. From the central perforated portion the drum has lateral conical extensions supporting the rims and forming the receiving and delivery sides or ends of the drum.

85 Into the conical extension 12 the articles are fed from hopper 14 and from this extension the articles pass on into the pickling chamber through an opening 13 in the partition wall.

90 This hopper is supported on the standard bracket 15 and has a lateral escape opening or passage 16 adjacent the drum through which any of the articles fed into the hopper may escape should it become caught or 95 jammed against the drum.

95 The articles such as screws pass from the hopper to the drum, while the latter remains at rest or is rotating, and as the drum revolves a cleat or pin 17 secured to and 100 extending inwardly from the periphery of the drum, collects the articles, carries them upwardly and deposits them in a chute 18 inclining outwardly through the conical extension 19 for discharging into a washing 105 drum 20.

From the washing drum the articles are fed into a conical extension 21 of the plating drum 22 from which they pass through partition wall opening 23 into the plating 110 chamber which contains the proper coating solution, such as for electro-plating with nickel.

By means of a blade 24 secured to and

extending inwardly from the periphery of the drum the coated articles are elevated and again discharged into the inclined chute 25 which leads to a second washing drum 5 26 that empties into a drying drum 41.

The two washing drums are substantially alike in construction, consisting of a rearwardly flaring, perforated casing having its forward end encircled by an oppositely 10 flared skirt 27 and a collecting shield 28 inclosing the remainder of the perforated casing. The skirt 27 is designed to direct all the drippings of the pickling and plating liquids back into their respective chambers, 15 discharging onto the connector 29 and the conical sections 19 and 30 of the pickling and plating drums. A spray pipe 31 enters the forward end of each washing drum and discharges downwardly onto the articles as 20 they pass over the perforations inclosed by the shield 29 whereby the washing liquid will pass through the perforations onto the shield. By reason of its configuration, the liquid is collected at the apex 32 which is 25 perforated to discharge into a drain pipe 33 over which it passes during rotation of the drum.

Peripheral track 34 on the washing drums are supported to run on the large drive 30 wheels 6 whereby the drums will be driven at a fast rate of speed as compared to the more slowly revolving pickling and plating drums.

The plating drum is electrically insulated 35 from its drive wheels 7 on which the peripheral tracks or rims 35 operate, by coating the interior of the drum with suitable insulating material, or the drum may be made of wood, as indicated in Fig. 5. The delivery chutes 18 and 25 are supported on an upstanding bracket 36, and depending from chute 25 within the plating chamber is a supporting hanger 37 having a pendulum-like electrode 38, pendent in the plating solution, and a weighted electrode 39 constructed to extend laterally above the plating solution but in proximity to the periphery of the drum.

This second electrode terminates in the 50 shape of a ball and is designed to rest upon the articles above the liquid and thereby establish electrical connection with those immersed. The electrode 39 is suspended from an insulated part of the hanger 37, and wires 40 electrically connect to a source of electrical energy.

The drying drum 41 is also perforated and equipped with peripheral tracks 41' operable over the supporting drive wheels 60 7. A spiral conveyer blade 42 is fixed within the drum for slowly advancing the material beneath a drying blast issuing downwardly from an axial conduit 43.

Briefly setting forth the operation, the 65 articles are placed within the feed hopper

which discharges them into the pickling drum where they are thoroughly cleansed and later washed in the first washing drum 20, from whence the articles follow into the plating drum 22. Subsequently to 70 traversing the second washing drum the articles are dried in drum 41 or in another type of drying drum exemplified in Figs. 7 and 8 which may be substituted for the first drum or arranged on the machine frame to 75 receive the articles from the said drum 41.

This second type of drier consists of two conical shells 45 and 46 arranged one within the other and in reverse manner, the inner shell having its larger end portion formed 80 of wire fabric 47 constituting a sieve. The articles are fed through pipe 48 into the smaller end of the inner shell and therewith is also supplied an absorbent material, such as saw dust, which absorbs the moisture 85 from the articles and later passes through the interstices of screen 47 into the outer shell whose opposite inclination reconducts the saw dust back to the feed end where it is again delivered by the flat spiral wall 49. 90 Obviously, revolving the drum on its peripheral tracks 50 will effect a continuous flow of saw dust, first with the articles and then in a reverse direction, the whole operation being automatic throughout. 95

The several steps of washing, coating and drying are carried on in a single, continuous operation of the machine, the washing drums being rotated at a faster rate of speed than the remaining drums.

The difference in speed between the drums is accomplished by the different sized wheels on the drive shaft which have frictional contact with their peripheral tracks. By reason of this friction drive no damage or 105 injury will be caused should a piece of work in any manner be caught between two drums. The operation is entirely automatic throughout requiring no attention on the part of the operator except in so far as the 110 supply of pickling and plating solutions may require replenishment.

Having thus described my invention, what I claim as new and desire to secure by Letters Patent is—

1. A metal coating machine comprising a pickling drum, a washing drum communicating therewith to receive the metal articles therefrom, a coating drum mounted to receive the articles from the washing drum, 120 a second washing drum for receiving the material from the coating drum, and a drying drum into which the second washing drum discharges, and a common drive for the drums whereby the articles will be continuously acted upon from one end of the machine to the other end in an automatic manner.

2. In a metal coating machine, a pair of parallel shafts, a plurality of independent 130

drums, and a pair of drive wheels fixed on each shaft for each drum for supporting and driving the same, the wheels supporting and driving one drum being of different

5 diameter than the wheels supporting and driving an adjacent drum whereby one drum will be rotated at a different speed than the adjacent drum.

3. In a coating machine, spaced pickling 10 and coating drums and an interposed washing drum independently rotatable, a common drive shaft for the drums, and wheels carried by the shaft for supporting and driving the respective drums, said wheels 15 having relatively different diameters.

4. In a machine of the nature described, spaced shafts, gearing connecting the same for simultaneous rotation, spaced pairs of drive wheels fixed on the shafts, the wheels of

20 both shafts being arranged in coating pairs, a pickling drum, a coating drum, and an interposed washing drum, all of said drums being rotatably and frictionally supported and driven by the wheels, the drive wheels

25 supporting the washing drum being larger than those supporting the other drums whereby to rotate said interposed drum faster.

5. In a machine of the nature described, spaced intergeared shafts, an interposed trough therebetween adapted to contain a pickling liquid, a pickling drum rotatably supported off and between the shafts and formed with a perforated periphery the 35 lower arc of which passes through the liquid contained in the trough, and means for removing metal articles from the drum by and during rotation thereof.

6. In a machine of the nature described, spaced shafts intergeared to rotate synchronously, an interposed container for pickling liquid, a pickling drum having spaced peripheral tracks supporting the drum off the shafts and constituting a frictional drive 45 therefor, said tracks straddling the container, and said drum having a peripherally perforated portion extending into the container, and a washing drum into which the chute discharges.

50 7. In a machine of the nature described, spaced intergeared shafts, an interposed container for pickling liquid, a pickling drum having peripheral tracks straddling the container, said drum having its lower arc extending into the container, a washing drum into which the pickling drum discharges, said washing drum having peripheral tracks, and sets of wheels fixed on the shafts and supporting the tracks so as to frictionally 55 drive the respective drums, said wheels supporting the washing drum being of larger diameter than those supporting the pickling drum.

8. In a machine of the nature described,

a rotatably supported drum adapted to contain a cleansing liquid for cleaning the articles placed therein, a trough leading therefrom to discharge the material from the drum, a washing drum of conical shape into which the material is discharged, said washing drum comprising a perforated casing having an encircling oppositely flaring skirt about its smaller end to direct the draining liquid from the material back into the first drum, and a collecting sheath inclosing an adjacent portion of the perforated casing, and a spray pipe arranged within the washing drum for discharging a washing spray onto the material as it moves over that portion of the casing inclosed by the sheath whereby the latter may receive the drainage from the material.

9. In a machine of the nature described, means for subjecting the material to a cleansing bath, means for washing the material as it is delivered from the first means, and means for electro-plating the material comprising a drum containing a coating solution, a swinging electrode depending into the coating solution, and a second electrode 90 also swingingly mounted but disposed above the solution so as not to become coated therewith and to engage the material as it emerges from the solution.

10. In a machine of the nature described, a rotatably mounted drum containing a plating solution, a blade extending inwardly from its periphery of the drum to carry the material being treated to the upper portion of the drum and discharge the same, a 100 trough into which the material is discharged for delivering same from the drum, a bracket support depending from the trough into the drum and having an insulated part, a pendulum like electrode extending from the 105 support down into the plating solution, and a second electrode supported by the insulated part and extending toward the periphery of the drum but free of the solution.

11. In a coating machine, a pickling drum, 110 a coating drum, and an interposed washing drum receiving from the first drum and delivering to the second drum, and means for rotating the washing drum faster than the first and second drums.

115 12. In a coating machine, a pickling drum, a coating drum, and an interposed washing drum receiving from the first drum and delivering to the second drum, and common means for supporting and driving the drums 120 at relatively different speeds.

In testimony whereof I have signed my name to this specification in the presence of two subscribing witnesses.
